UNITED STATES PATENT OFFICE.

ADOLFO C. RIGGS, OF COVINA, CALIFORNIA.

REMOVABLE COVER.

Application filed June 23, 1925. Serial No. 39,029.

To all whom it may concern:

Be it known that I, ADOLFO C. RIGGS, a citizen of the United States, residing at Covina, in the county of Los Angeles and 5 State of California, have invented new and useful Improvements in Removable Covers, of which the following is a specification.

My invention is a removable cover adapted to be attached to various sizes of barrels 10 or kegs to form a temporary closure.

The invention pertains to closures or covers for barrels or kegs in which produce is displayed for sale and in which it is desired to have a cover of neat appearance which 15 will allow inspection of the goods and which will also form a tight cap or covering on the barrel or keg to prevent entrance of dirt, flies or the like.

One of the features of my invention is a 20 clamp adapted to be secured around the upper rim of the barrel and having a capping ring extending inwardly over the top of the barrel. In the device illustrated the capping ring is of a fixed and standard size, 25 whereas the clamping strap is so constructed as to accommodate barrels of considerable difference in diameter. A lid, preferably formed of glass, is hinged to one side of the capping ring and is also swivelled to 30 the ring so that the lid may be swung around completely out of the way for filling or cleaning the barrel or container.

My invention will be more readily understood from the following description and 35 drawings, in which;

Figure 1 is a perspective view of my removable cover secured to the top of a barrel.

Fig. 2 is a cross sectional elevation on the 40 line 2-2 of Fig. 1, showing the removable cover detached from the barrel.

Fig. 3 is a horizontal section on the line 3-3 of Fig. 2 in the direction of the arrows, showing the clamping straps.

Fig. 4 is an enlarged detail of a section 45 shown in Fig. 3, illustrating the manner of securing the glass to the lid ring.

Fig. 5 is a plan of the hinge in the direction of the arrow 5 of Fig. 1, showing the 50 manner of mounting the hinge and the swivel to give two motions to the lid.

In the illustrations a barrel, keg or the like is designated by the numeral 1, in which even in standard sized barrels or kegs the 55 upper edge or rim 2 varies considerably in

diameter. Moreover, barrels and kegs of different makers differ to such an extent that a fixed or definite sized lid does not make a satisfactory removable cover. The removable cover is designated generally by the numeral 3 and is constructed in detail with an adjustable clamping strap and a fixed sized lid.

The strap 4 comprises right and left sections 5 and 6 secured by clamp screws 7. 65 Each of the sections 5 and 6 are preferably formed of similar straps 8 and 9 having eyes 10 formed by bending the straps through which extends capping ring pins or rivets 11. Each of the sections 8 and 9 70 have outwardly extending lugs or flanges 12 through which the clamp screws 7 extend. In order to allow quick adjustment one of the flanges may have an aperture 13 and the other a slot 14 so that the clamp screws 7 75 may be readily inserted and clamped tight by a thumb nut 15. In this manner the clamping strap is formed of two pair of hinged straps connected by a pin so that they may swivel and the two pairs or sets 80 of straps may be drawn tightly together to form a tight clamp on the rim of the barrel. This also adds to the strength of the barrel in handling.

A capping ring 16 formed of preferably 85 a flat annulus of metal of sufficient width to cover all the various sizes of barrels to which the clamping strap may be accommodated, is secured to the strap by the rivets 11, the connection being sufficiently loose to 90 allow the strap to be tightened or loosened as required.

The lid designated generally by the numeral 17 is built up with a lid ring 18 having a vertical flange 19 and a horizontal 95 flange 20. A sheet of glass or the like, 21, having a rubber or other resilient packing ring 22 is clamped to the underneath surface of the horizontal flange by means of bolts 23 secured to a stop ring 24. In this 100 manner by tightening the bolts the ring 24 may be pressed against the lower surface of the glass evenly and form a tight closure with the lid ring 18.

The lid 17 is provided with a hinge 25 105 having a fixed plate 26 secured to the lid ring 18 by means of rivets 27 and having a horizontal hinge pin 28 connecting the fixed plate with a swivel plate 29. This latter is secured to the capping ring 16 by 110

means of a swivel pin 30. This pin has suitable heads to allow swivelling of the lid on a vertical axis and also allows the lid to be folded backwards on the horizontal pin 5 28. Where merchandise such as fruit or the like can be removed from the barrel with one hand it is more convenient to raise the lid on its horizontal hinge, but if both hands are required such as removing butter from a butter tub it is more convenient 10 to swivel the lid on the vertical swivel pin. The hinge may be arranged and the swivel pin so positioned that when swivelled the lid will hang downwardly alongside of the 15 barrel or tub and thereby be out of the way.

The particular construction of my removable cover may be considerably changed to adapt it for use with different materials. The construction shown is formed with a 20 metal frame but a wood construction could readily be adapted for the purpose and have the same general characteristics. Moreover, my device may be adapted to cover square or rectangular boxes or other irregular shaped containers. Thus, various removable 25 covers may be made in accordance with the spirit of my invention having a clamping device which may be accommodated to various sizes of containers within reasonable 30 limits and having a fixed capping ring or the like to form a closure on the top of the container with a lid attached thereto.

Having described my invention, what I claim is:

35 1. A removable cover comprising in combination a plurality of flexible straps connected in pairs, pins forming a pivotal connection for said pairs of straps, clamping screws connecting each pair of flexible 40 straps together, said straps and connections allowing the straps to be clamped to various sized containers, a fixed sized capping

ring secured to said pins, said ring comprising a horizontal flat annulus and a lid connected to the capping ring and adapted to 45 be opened or closed.

2. A removable cover comprising in combination a plurality of flexible straps connected in pairs by means of a pivotal connection, clamping screws connecting each 50 pair of flexible straps together, said straps and connection allowing the straps to be clamped to various sized containers, a fixed sized capping ring secured to the clamping straps, said ring comprising a horizontal 55 flat annulus, a lid, a hinge having a fixed plate secured to the lid, a horizontal hinge pin, a swivelling plate connected to the pin and a vertical swivel pin through the swivel plate connecting the swivel plate to the capping ring, said swivel pin being positioned whereby the lid may be swivelled vertically and hinged downwardly to hang along the side of the container.

3. A removable cover comprising in combination a clamping strap comprising two pairs of flexible strap elements, said elements having an eye and a pivotal pin therefor, the free ends of said strap elements having flanges and clamp screws engaging 70 said flanges, a capping ring comprising a horizontal flat annulus connected to the said pivotal pins and a lid hinged to said capping ring.

4. A removable cover as claimed in claim 75 3 having in addition a vertical swivelling connection between the hinge and the capping ring whereby the lid may be swivelled on a vertical axis and hinged downwardly 80 along the side of the container.

In testimony whereof I have signed my name to this specification.

A. C. RIGGS.
